UNITED STATES PATENT OFFICE

92,947

DESIGN FOR A WATER HEATER

Edward Chase Crowley, New York, N. Y., assignor
to F. MacGovern Corporation, New York, N. Y.,
a corporation of New York

Application February 14, 1934, Serial No. 50,733

Term of patent 14 years

To all whom it may concern:

Be it known that I, EDWARD CHASE CROWLEY, a citizen of the United States and resident of New York city, in the county of New York and State of New York, have invented a new, original, and ornamental Design for a Water Heater, of which the following is a specification, reference being had to the accompanying drawing forming part thereof.

The figure is a perspective view of an electric water heater showing my new design.

I claim:

The ornamental design for a water heater, as shown.

E. CHASE CROWLEY.
